FIG. 7

FIG. 8

FIG. 9

FIG. 1 is an isometric view of a nebulizer-humidifier showing my new design;

FIG. 2 is a top plan view of the embodiment of FIG. 1;

FIG. 3 is a front elevational view of the embodiment of FIG. 1, the rear elevational view being a mirror image thereof;

FIG. 4 is an elevational view from the right side of FIG. 1;

FIG. 5 is an elevational view from the left side of FIG. 1;

FIG. 6 is an isometric view of a second embodiment of a nebulizer-humidifier of my new design wherein the sole difference resides in structure provided for attachment of a gas inlet adapter;

FIG. 7 is a top plan view of an embodiment of FIG. 6;

FIG. 8 is a front elevational view of the embodiment of FIG. 6, the rear elevational view being a mirror image thereof; and

FIG. 9 is an elevational view of the left side of FIG. 6, an elevational view of the right side of FIG. 6 being identical to FIG. 4.

The undisclosed bottom portion of the container is plain and unornamented.

This is a continuation-in-part of my co-pending application Ser. No. 468,435, filed May 9, 1974, and now abandoned.

I claim:

The ornamental design for a nebulizer-humidifier container for inhalation therapy, as shown and described.
